US0D1012889S

(12) **United States Design Patent** (10) **Patent No.:** **US D1,012,889 S**
Zhong et al. (45) **Date of Patent:** **** Jan. 30, 2024**

(54) **HEADPHONES**

(71) Applicant: **SHENZHEN SHOKZ CO., LTD.**,
 Guangdong (CN)

(72) Inventors: **Lei Zhong**, Shenzhen (CN); **Zhi Cai**,
 Shenzhen (CN); **Sunjie Huang**,
 Shenzhen (CN); **Zeteng Yan**, Shenzhen
 (CN); **Qian Chen**, Shenzhen (CN);
Piyou Cheng, Shenzhen (CN);
Yueqiang Wang, Shenzhen (CN)

(73) Assignee: **SHENZHEN SHOKZ CO., LTD.**,
 Shenzhen (CN)

(**) Term: **15 Years**

(21) Appl. No.: **29/792,742**

(22) Filed: **Apr. 21, 2022**

(30) **Foreign Application Priority Data**

Oct. 22, 2021 (CN) 202130694639.5

(51) **LOC (14) Cl.** **14-01**

(52) **U.S. Cl.**
 USPC **D14/206**; D14/226

(58) **Field of Classification Search**
 USPC D14/206, 226, 205, 249, 251; D29/112;
 2/209; 381/380-381, 374
 CPC H04R 25/00; H04R 25/02; H04R 1/1066;
 H04R 1/1016; H04R 5/033; H04R
 5/0335; H04R 1/1041; H04R 1/1091;
 H04R 11/04; H04R 19/04; H04R 1/08

(57) **CLAIM**

The ornamental design for headphones, as shown and described.

DESCRIPTION

FIG. 1 is a right perspective view of headphones showing our new design;

FIG. 2 is a left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
